INVENTOR.

Arthur J. Weed

UNITED STATES PATENT OFFICE.

ARTHUR J. WEED, OF NEW YORK, N. Y.

T-SQUARE HOLDER.

SPECIFICATION forming part of Letters Patent No. 375,030, dated December 20, 1887.

Application filed May 19, 1887. Serial No. 238,801. (No model.)

To all whom it may concern:

Be it known that I, ARTHUR J. WEED, a resident of New York, in the county of New York and State of New York, have invented 5 a new and useful T-Square Holder, of which the following is a specification.

My invention relates to improvements in T-square holders in which the head of the T-square is held against the side of the drawing-board by the compression of a spring attached to and forming part of the holder; and the objects of my invention are, first, to hold the T-square in the proper position on the drawing-board by an implement placed on the T-square 15 blade at a distance from the head of the T-square corresponding to the size of the drawing-board; second, to attach the implement to the blade of the T-square in such a manner that it can be instantly adjusted for any size 20 of drawing-board consistent with the length of the T-square; third, to attach the implement to the T-square blade firmly without injury to the edge of the blade; fourth, to hold the T-square in position on the drawing-board by the compression of a spiral spring; and, fifth, to hold the T-square in proper position at any 25 point on the drawing-board regardless of the angle which the drawing-board may assume from a horizontal plane. I attain these objects by the mechanism illustrated in the accompanying drawings, in which—

Figure 1 is an elevation in perspective of the implement. Fig. 2 is a bottom view of the implement. Fig. 3 is an end view of the implement, and Fig. 4 is a top view of a drawing-board and T-square with the implement attached.

Similar letters refer to similar parts throughout the several views.

40 The plate A, having the projections H I underneath, form the body of the implement. In each of the projections H I is drilled a hole at an equal distance from the under side of the plate A, through which the bar C can slide 45 freely. To one end of the bar C is secured the head E, the face of which is slightly rounded to prevent it from injuring the grain of the wood when slid along the side of the drawing-board F. Around the bar C, between the projections H and I, is the spiral spring D, which is compressed between the projection I and the washer a. Passing through the bar C is the

pin b, against which the washer a is held by the compression of the spring D. The pin b passes through the bar C at a point where it will 55 strike the projection H, thereby preventing the bar C from being driven out of the projection I by the expanding of the spring D, all of which is shown in Fig. 2. The clamp B holds the plate A firmly against the under side of 60 the T-square blade G. The ends of the clamp B turn downward at right angles, and are parallel with each other, as shown in Figs. 1 and 3. The two ends of the clamp B pass through two holes in the plate A, as shown in Fig. 1. 65

Secured to the ends of the clamp B are the heads or washers c c, as shown in Figs. 2 and 3. Around each end of the clamp B, after they pass through the two holes in the plate A, are the spiral springs d d, which, being compressed between the under side of the plate A and the heads or washers c c, hold the plate A firmly against the under side of the T-square blade G. The screws e e, the lower ends of which are pointed, pass through the clamp B, 70 Fig. 1, and can be adjusted to indent the upper side of the T-square blade G sufficiently to prevent the implement from sliding thereon. 75

To apply the implement to the T-square blade, it is taken between the thumb and finger of each hand, as shown in Fig. 1, thus compressing the springs d d and making an opening for the T-square blade between the clamp B and the plate A.

When in use, the implement is attached 85 firmly to the T-square blade G by the clamp B.

The spring D, acting through the washer a, the pin b, and the bar C, holds the head E against the side of the drawing-board F. The spring D in holding the head E against the 90 side of the drawing-board F in the above combinations exerts a reaction against the projection I, which, acting through the plate A, the clamp B, and the T-square blade G, holds the head of the T-square J against the side of the 95 drawing-board F with a force corresponding to the amount of compression which has been applied to the spring D. The compression of the spring D is varied by placing the implement on the blade of the T-square nearer to or 100 farther from the drawing-board F.

I am aware that prior to my invention T-square holders have been made for holding the head of the T-square against the side of the

drawing-board. I therefore do not claim such an invention, broadly; but

What I do claim as my invention, and desire to secure by Letters Patent, is—

5 In a T-square holder, the combination of the plate A, having projections H I, with the clamp B, the washers c c, the springs d d, the screws

e e, the bar C, the head E, the spring D, the washer a, and the pin b, all substantially as shown, for the purpose specified.

ARTHUR J. WEED.
